(57) **CLAIM**

The ornamental design for a battery for wearable physiological monitor, as shown and described.

DESCRIPTION

FIG. 1 is a top perspective view of a design for a battery for wearable physiological monitor;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top-front perspective view thereof, engaged with a wearable physiological monitor and strap;
FIG. 9 is a top-rear perspective view thereof;
FIG. 10 is a top-front perspective view thereof, partially engaged with a wearable physiological monitor and strap;
FIG. 11 is a bottom-rear perspective view thereof; and,
FIG. 12 is a top perspective view thereof, engaged with a wearable physiological monitor and strap on a user's wrist. The broken line showing of the physiological monitor, strap, and user's wrist illustrate environmental structure and form no part of the claimed design. All other broken lines illustrate portions of the battery for wearable physiological monitor and form no part of the claimed design.
